CLAIM

The ornamental design for a drum key multi-tool, as shown and described.

DESCRIPTION

FIG. 1 is a front top left perspective view showing my new design for a drum key multi-tool.

FIG. 2 is a back top right perspective view thereof.

FIG. 3 is a front bottom right perspective view thereof.

FIG. 4 is a front bottom left perspective view thereof.

FIG. 5 is a back view thereof.

FIG. 6 is a left side view thereof.

FIG. 7 is a front view thereof.

FIG. 8 is a right side view thereof.

FIG. 9 is a bottom view thereof; and,

FIG. 10 is a top view thereof.

Features shown in the drawings in broken lines form no part of the claimed design.
